BERTHA S. ALSOP, OF NEW YORK, N. Y.

BOTTLE.

1,155,333.

Specification of Letters Patent.

Patented Oct. 5, 1915.

Application filed March 25, 1914. Serial No. 827,028.

To all whom it may concern:

Be it known that I, BERTHA S. ALSOP, a citizen of the United States of America, and residing at New York, in the county of New York and State of New York, have invented new and useful Improvements in Bottles, of which the following is a specification.

One object of my invention is to produce a bottle which for all practical and commercial purposes shall be non-refillable.

My invention has as a further object to prevent pouring of the contents of the bottle in case it has been found possible in some way to refill the once-emptied bottle. Even if refilled, it will be impossible to reuse the bottle.

These objects are attained by using a buoyant valve which consists usually of two parts, a floatable body and a flexible seal. A guard or guards are also provided for preventing mechanical access to the valve or valves for the purpose of manipulation. When the bottle is tipped up to pour out the liquid, the valve automatically opens by gravity and the pressure of the liquid. When the bottle is stood upright, the valve closes automatically by gravity. The guarding means in the preferred form serves also as a weight to assist in closing the valve and to hold the valve positively closed when the bottle is upright. This positive closure of the valve obviates possibility of refilling the bottle in an upright position. The buoyant character of the valve prevents refilling of the bottle in reversed position because in that case any attempted inflow of liquid floats the valve to its seat. When pressure is used in an attempt to force the liquid into the bottle, the valve is forced backward

against a stop and locked by the flexible seal so that it will not open again. This prevents the emptying of the bottle in case it has been found possible to refill it and consequently prevents the reuse of the bottle after it has been once emptied.

Figure 1, shows a cross section of the neck of a bottle embodying one form of the improvements of my invention. Fig. 2, is a view similar to Fig. 1, but with the bottle tilted in the pouring position. Fig. 3, is a drop view of the several parts which co-operate to form the bottle closure. Fig. 4, is a top plan view of these parts, omitting the valve seat and bottle neck. Fig. 5, is a fragmentary sectional view showing how the valve is locked after it has been forced back

by pressure. Fig. 6 is a sectional view of the neck of the bottle showing a slightly modified form of float.

As above indicated, the valve is buoyant and consists usually of two parts, a body part 7 and a thin flexible seal 8 which normally engages with the valve seat. This seal may be made of any suitable material which is unaffected by the liquid contained in the bottle and which will not affect the liquid. The necessary buoyancy may be given the valve by making the valve body hollow or of buoyant material, but in the present instance, buoyancy is obtained by attaching a float 9 of cork or similar material to the valve body. The float may be attached to the valve body by simply forcing it into a seat or opening 10 formed in said valve body, the float in some cases having a reduced lower end 11 as indicated in Fig. 3 which fits tightly in the said opening. This reduced end of the float provides a shoulder 12, between which and the valve body the flexible seal may be clamped. This is a convenient and practical way for securing the valve body and flexible seal together. The edge of the valve body is preferably corrugated or fluted as shown at 13 and fits loosely within the passage 14 in the bottle neck 15. The edge of the seal 8 normally seats on the shoulder 16, at the outer end of passage 14. This shoulder, which in practice forms the valve seat, may be an integral part of the bottle neck, but usually it is carried by a separate annular valve seat member 18 which is engaged with the end of the bottle neck.

The outward opening movement of the valve is limited and controlled in the present instance by two movable guards, an inner one 20, and an outer one 21. The inner guard, as clearly appears in Fig. 1, normally rests upon the flexible seal and therefore serves as a weight to hold the valve closed. This guard member is shown provided with a central passage 22 receiving the float portion of the valve and it may be recessed as at 23 on its lower end surface to receive the flexible seal. This permits the guard to rest at its outer edge upon the valve shoulder so that the valve is held closed by the guard without requiring the entire weight of the guard to be borne by the flexible seal. The upper or outer guard 21, in the illustration, rests directly upon the inner guard and is provided in its sides with passages 25 permitting lateral access of liq-

uid to the top of the float. The inward movement of the valve is limited by the shoulder 27.

The movable guards and the valves are all inclosed within a casing 29 which, as shown, may be in the form of a cap, provided with a central pouring outlet 30, and secured to the bottle neck by a retaining ring 31. The upper end of the inner guard 10 preferably engages the walls of the casing with a loose sliding fit while the lower end is somewhat smaller, as shown. This permits the guard to have a tilting as well as a sliding valve-closing movement.

15 A tortuous passage for the liquid is provided by grooving the sides of the inner guard member 20, as indicated at 32 and providing openings 33 in the outwardly flaring flange 34 of the upper crown-shaped guard 21, so that the liquid is forced to flow up along the sides of the inner guard and laterally across the top of the upper guard to the pouring mouth or outlet. The top of the upper guard may be dished as indicated 20 to afford a large air space and to make more difficult the insertion of an instrument in the outlet grooves.

For the purpose of guiding the valve in its movements, the float, may, as shown in 30 the first five figures, be provided with a longitudinal passage 36, receiving a guiding stem 37 which may be carried by the outer guard member. When the bottle is tilted, the valve guards and the valve move outward slightly and the liquid passes through the flutes 13 out from under the seal 8, up along the sides of the inner guard and laterally across the top of the upper guard to the central pouring opening. The weight 35 of the guard or guards holds the valve closed and this renders it impracticable to refill the bottle when in an upright position. Refilling by inverting and dipping the bottle into a tank is frustrated by the liquid, as it rises 40 in the bottle neck, flowing laterally through passages 25 and floating the valve up into engagement with its seat. When it is attempted to refill the bottle by the application of external force, the valve will be 45 pushed inward and the edges of the seal 8 will be thereupon engaged beneath the shoulder 40 which thereupon forms a valve seat in the passage 14 so that it will thereafter be impossible to pour out the liquid. 50 This shoulder 40 may as shown, be carried by the separate annular valve seat member 18. Instead of employing a float formed as described, a cork of the proper size may be used as indicated at 43 in Fig. 6. In this 55 case the valve may be guided by having the larger end of the cork engaging the walls of the passage 22 in the guard. With this construction it is practically impossible to tamper with the valve or refill the bottle and 60 even if some liquid is forced into the bottle

it cannot be poured out. It is obvious that no one who is familiar with the peculiarity of this locking valve construction will attempt to refill the bottle and there is no danger that a bottle which has been refilled 70 will be used to supply a substitute for the original liquid.

What I claim is:—

1. In combination, a bottle provided with a liquid passage and a valve seat, a buoyant 75 valve body engaged in the said passage, means limiting the inward movement of the valve body within the liquid passage and a flexible seal carried by the valve body, extending beyond the valve body and resting 80 upon the valve seat and adapted upon application of pressure to the valve to be carried by the valve body down into engagement with the walls of the passage at a point below the valve seat. 85

2. In a bottle, a valve seat surrounding a liquid passage, a buoyant valve for said passage comprising a body located in said passage and a flexible seal carried by said body extending over the outer edges of said body 90 and over said valve seat, and a stop for limiting the inward displacement of said body and flexible seal into the liquid passage. 95

3. In combination, a bottle provided with an outlet passage, seats surrounding said 100 passage and facing in opposite directions, and a floatable valve normally engaging the outer one of said seats displaceable by the application of force thereto into operative relation with respect to the inner seat. 105

4. In combination, a bottle provided with a liquid passage, a valve seat surrounding said passage, a buoyant valve body engaged in the said passage, a stop limiting the inward movement of the valve body within the passage and a flexible seal carried by the valve body, extending beyond the outer edges of the valve body to thereby normally rest upon the surrounding valve seat and adapted upon application of pressure to the valve to be carried by the valve body down into the passage and into engagement with the walls of the passage at a point below the valve seat. 110

5. In a bottle, a valve seat surrounding a liquid passage, a buoyant valve for said passage comprising a body located in said passage and a flexible seal extending over the outer edges of said body and said seat, a stop for limiting the inward movement of said body and a shoulder for coacting with said seal to lock said valve when the valve has been forced inward. 115

6. In combination, a bottle provided with an outlet passage and a valve seat, a buoyant valve body guided in said passage and engaging the valve seat aforesaid, the said buoyant valve being unattached to the bottle and free to move bodily in respect to the valve seat and a movable sliding and tilt- 120 125 130

ing weight confined in the bottle neck above the valve recessed to receive the valve therein, provided with a passage therethrough for liquid and normally bearing on the 5 valve to hold the valve seated against the valve seat, the said weight and the confining walls of the bottle neck being relatively inclined to facilitate the tilting valve-closing movement of the weight.

10 7. In combination, a bottle provided with an outlet passage and a valve seat surrounding said passage, a valve body fitting in the outlet passage and guided thereby, a float secured on top of said valve body and an 15 outstanding flexible seal clamped between

the valve body and float and arranged to engage the valve seat aforesaid.

8. In combination with a bottle provided with an outlet passage and a valve seat, a flexible valve engaging said valve seat and 20 a float on top of said flexible valve smaller at its lower end than the valve seat to thereby permit said valve being forced by external pressure down into engagement with the walls of the passage below the valve seat. 25
